US0D1009849S

(12) **United States Design Patent** (10) **Patent No.:** **US D1,009,849 S**
(45) **Date of Patent:** **** Jan. 2, 2024**

(54) **HOLDER FOR MOBILE DEVICE**

(71) Applicant: **CASE-MATE, INC.**, Atlanta, GA (US)

(72) Inventor: **Madison Rae Marie Schmidt**, Minneapolis, MN (US)

(73) Assignee: **CASE-MATE, INC.**, Atlanta, GA (US)

(**) Term: **15 Years**

(21) Appl. No.: **29/760,270**

(22) Filed: **Nov. 30, 2020**

(51) LOC (14) Cl. **14-99**

(52) U.S. Cl.

USPC **D14/253**

(58) **Field of Classification Search**

(57) **CLAIM**

The ornamental design for a holder for a mobile device, substantially as shown and described.

DESCRIPTION

FIG. 1 is a first perspective view of a holder for a mobile device.

FIG. 2 is a second perspective view of the holder for a mobile device of FIG. 1.

FIG. 3 is a side view of the holder for a mobile device of FIG. 1.

FIG. 4 is a top view of the holder for a mobile device of FIG. 1.

FIG. 5 is a bottom view of the holder for a mobile device of FIG. 1; and,

FIG. 6 is a perspective view of the holder for a mobile device of FIG. 1, shown in use attached to a mobile device and held by a user.

The broken lines showing a mobile device and hand in FIG. 6 depict environment that forms no part of the claimed design.

1 Claim, 3 Drawing Sheets
